US00D929367S

(12) **United States Design Patent** (10) **Patent No.:** **US D929,367 S**
(45) **Date of Patent:** **** Aug. 31, 2021**

(54) **SPEAKER**

- (71) Applicant: **Amazon Technologies, Inc.**, Seattle, WA (US)
- (72) Inventors: **Michael Edward James Paterson**, San Francisco, CA (US); **Giles David Matthew McWilliam**, San Francisco, CA (US); **Marc Rene Walliser**, San Francisco, CA (US)
- (73) Assignee: **Amazon Technologies, Inc.**, Seattle, WA (US)

(**) Term: **15 Years**

(21) Appl. No.: **29/650,422**

(22) Filed: **Jun. 6, 2018**

(51) LOC (13) Cl. **14-01**
(52) U.S. Cl. **D14/216**

(57) **CLAIM**

The ornamental design for a speaker, as shown and described.

DESCRIPTION

FIG. 1 is a top perspective view of a first embodiment of a speaker. The crosshatched pattern shown on the views of the first embodiment represents a fabric (e.g., a woven fabric), and is understood to be distributed uniformly over the surface of the claimed design upon which the pattern occurs; FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a top perspective view of a second embodiment of a speaker. The crosshatched pattern shown on the views of the second embodiment represents a fabric (e.g., a woven fabric), and is understood to be distributed uniformly over the surface of the claimed design upon which the pattern occurs;

FIG. 10 is a bottom perspective view thereof;

FIG. 11 is a front view thereof;

FIG. 12 is a back view thereof;

FIG. 13 is a left-side view thereof;

FIG. 14 is a right-side view thereof;

FIG. 15 is a top view thereof; and,

FIG. 16 is a bottom view thereof.
